UNITED STATES PATENT OFFICE.

ALOIS FAHRMBACHER, OF BERLIN-CHARLOTTENBURG, GERMANY, ASSIGNOR TO
SIEMENS SCHUCKERTWERKE G. M. B. H., OF SIEMENSSTADT, NEAR BERLIN,
GERMANY, A CORPORATION OF GERMANY.

MEANS FOR PREVENTING SPARKING IN DIRECT-CURRENT MACHINES.

1,215,787.

Specification of Letters Patent. Patented Feb. 13, 1917.

Original application filed October 22, 1912, Serial No. 727,131. Divided and this application filed January 21, 1915. Serial No. 3,527.

To all whom it may concern:

Be it known that I, ALOIS FAHRMBACHER, a German citizen, and resident of Berlin-Charlottenburg, Germany, have invented 5 certain new and useful Improvements in Means for Preventing Sparking in Direct-Current Machines, of which the following is a specification.

This application is a division from an application filed by me in the United States Patent Office under date of October 22, 1912, and having Serial No. 727,131.

My invention relates to improvements in processes and means for preventing sparking 15 in direct-current machines of the type described in the application Ser. No. 651,794, and a primary object is to obtain a commutating field which is as favorable as possible with a wide range of speed.

20 To this end, I provide the auxiliary machine with a second field winding which opposes the main field-winding thereof through which flows the main current or a part of the same.

25 The invention consists in the combination of parts described hereinafter and pointed out in the claims.

The invention is diagrammatically represented in the accompanying drawing, where- 30 in:—

Figure 1 shows one form of my invention in which the auxiliary machine has a self-exciting shunt winding which opposes the main field-winding thereof;

35 Fig. 2 shows another form, in which the auxiliary machine has a counter compound-ing winding;

40 Fig. 3 shows a modified form corresponding to that shown in Fig. 2, but in which the main field-winding of the auxiliary machine is connected in parallel with the commutating winding of the main machine;

45 Fig. 4 shows another modification in which the main field-winding of the auxiliary machine is connected in shunt to the compensating winding of the main machine;

50 Fig. 5 shows another modification in which the main field-winding of the auxiliary machine is connected in shunt across both the compensating winding and the 55 commutating winding of the main machine.

Fig. 6 is a diagram showing the variations of commutating fields with the speed.

In the above-mentioned application Serial No. 651,794 an arrangement for preventing 55 sparking in direct-current machines is described, in which the commutating field is influenced by an auxiliary machine which runs synchronously with the main machine and works on a second commutating winding connected oppositely to the commutating winding proper. Consequently, when the speed increases the commutating field is weakened. A commutating field is obtained 60 which corresponds fairly exactly to the curve I in Fig. 6 of the present application, which is Fig. 1 of the parent application and which indicates the dependence of the commutating field F on the number of revolutions N when the strength of current remains constant.

Now it has been found by tests that such a commutating field as indicated by the curve I of Fig. 6 does not result into the most favorable commutating conditions. 75 On the contrary, a commutating field curve, as indicated by the curve II in Fig. 6 would correspond to the most favorable commutation. This curve II at first tends to run approximately coincident with curve I; at 80 high speed however, it tends to run approximately parallel with the axis of the abscissas.

Now in order to obtain as favorable a commutating field curve as possible, I provide 85 the auxiliary machine with a second field winding which opposes the main field-winding through which the main current or a part of the same passes.

Such an arrangement is shown for example in Fig. 1. The main machine is here designated *a*, while *h* denotes the auxiliary machine; *f* is the main field-winding of the main machine and *e* the main field-winding 90 of the auxiliary machine. In this arrangement the auxiliary machine is provided with a self-exciting shunt winding *n* which acts oppositely to the main field winding *e*. Consequently the excitation of the auxiliary machine *h* is at first weakened only little, while 95 when the speed increases it is weakened more. Consequently, in this arrangement the course of the commutating field represented by curve II in Fig. 6 is obtained. The 100 action of the shunt winding corresponds to the difference *d* of the curves I and II in

Fig. 6 which is only small at low speeds, while it is greater at high speeds.

A similar effect is obtained by the arrangement represented in Fig. 2, in which the auxiliary machine h is provided with a counter compound winding k which likewise opposes the main field-winding e . According to the invention it is thus immaterial whether the second winding n or k of the auxiliary dynamo be fed in series or in shunt by the armature h . It is essential, however, that the second field-winding n or k shall oppose the main field-winding e . Moreover, the main field-winding e may be fed in series by the main current, as is represented in Figs. 1 and 2.

On the other hand, as shown by way of example in Fig. 3, which otherwise corresponds with the arrangement shown in Fig. 2, the field-winding e may be connected in parallel with the commutating winding w of the main machine, or, as in Fig. 5, be connected in shunt to the compensation winding c , or, as in Fig. 6, be connected in shunt across the compensation winding c and the commutating winding w connected in series.

I claim:—

1. In a direct-current dynamo electric machine of the character described, the combination of a main dynamo having a commutating winding; an additional winding for counteracting said commutating winding; an auxiliary dynamo coupled with said main dynamo for supplying current to said additional winding; and means for varying the voltage of said auxiliary dynamo in a predetermined manner as a non-linear function of the speed.
2. In a direct-current dynamo electric machine of the character described, the combination of a main dynamo having a commutating winding; an additional winding for counteracting said commutating winding; an auxiliary dynamo coupled with said main dynamo for supplying current to said additional winding; and means for changing the voltage of said auxiliary dynamo in dependence of its speed more rapidly at relatively low speed and less rapidly at relatively high speed.
3. In a direct-current dynamo electric machine of the character described, the combination of a main dynamo having a commutating winding; an additional winding for counteracting said commutating winding; an auxiliary dynamo coupled with said main dynamo for supplying current to said additional winding; and means for varying the voltage of said auxiliary dynamo so as to more slowly increase at relatively high speed and so as to more rapidly increase at relatively low speed.

4. In a direct current dynamo electric machine of the character described, the combination of a main dynamo having a commutating winding; an auxiliary dynamo geared to said main dynamo; an additional winding mounted to coöperate with said commutating winding; connections between said auxiliary dynamo and said additional winding for counteracting the effect of said commutating winding with increasing speed of said main and said auxiliary dynamo; a main field-winding for said auxiliary dynamo connected to be energized in dependence on the current generated by the armature of said main dynamo; and a further winding on said auxiliary dynamo which is excited from the armature thereof and mounted to oppose the action of the main field-winding thereof.

5. In a direct current dynamo electric machine of the character described, the combination of a main dynamo having a commutating winding; an auxiliary dynamo geared to said main dynamo; an additional winding mounted to coöperate with said commutating winding; connections between said auxiliary dynamo and said additional winding for counteracting the effect of said commutating winding with increasing speed of said main and said auxiliary dynamo; a main field-winding for said auxiliary dynamo connected to be energized in dependence on the current generated by the armature of said main dynamo; and a shunt winding on said auxiliary dynamo connected to oppose the action of the main field-winding thereof.

6. In a direct-current dynamo electric machine of the character described, the combination of a main dynamo having a commutating winding; an auxiliary dynamo geared to said main dynamo; an additional winding on said main dynamo in the axis of said commutating winding; connections between said auxiliary dynamo and said additional winding for opposing the action of said commutating winding with increasing speed of said main and auxiliary dynamo; a main field-winding on said auxiliary dynamo which is connected in series to the armature of said main dynamo; and a self-exciting shunt winding on said auxiliary dynamo connected to oppose the action of the main field-winding thereof.

In testimony whereof I have hereunto set my signature in the presence of two subscribing witnesses.

ALOIS FAHRMBACHER.
